[57] **CLAIM**

We claim the ornamental design for the floating cooler, as shown and described herein.

DESCRIPTION

FIG. 1 is a perspective view of a floating cooler showing my new design;

FIG. 2 is a top view of a floating cooler showing my new design;

FIG. 3 is a left side view of a floating cooler showing my new design, wherein the right side is a mirror image thereof; FIG. 4 is a front end view of a floating cooler showing my new design;

FIG. 5 is a rear end view of a floating cooler showing my new design; and,

FIG. 6 is a bottom view of a floating cooler showing my new design.

The rope that ties the two pieces of the cooler together is not shown in FIGS. 1,2 and 6 for ease of illustration.
